UNITED STATES PATENT OFFICE.

GEORGE WOODWARD, OF NEWARK, NEW JERSEY, ASSIGNOR TO IGOE BROS., A CORPORATION OF NEW JERSEY.

REEL CARRIER.

Application filed April 15, 1920. Serial No. 374,045.

To all whom it may concern:

Be it known that I, GEORGE WOODWARD, a citizen of the United States, residing at Newark, in the county of Essex and State of New Jersey, have invented certain new and useful Improvements in Reel Carriers; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention relates, generally to improvements in that class of devices for the supporting and mounting thereon of coils of wire, rope, and the like; and, the present invention has reference, more particularly, 20 to a novel support in the form of a standard which is provided with supporting means for mounting upon the standard a plurality of reels, each reel carrying a coil of wire, rope, or the like, for feeding the several 25 coils independently, and at the same time, to different machines, or other different points of location.

The present invention, therefore, has for its principal object to provide a novel and 30 simply constructed support, in the form of a standard, carrying a plurality of reel-receiving and supporting members or elements, upon each one of which may be removably placed a reel carrying a coil of 35 wire, rope, or the like, said reel-receiving and supporting elements being preferably rotatably disposed with relation to the post or standard upon which said elements are 40 mounted, so that the coil-carrying reels can be variously arranged with a group of machines to which the wire is to be fed; and, furthermore, that one standard can be 45 used for the purpose of feeding wire at one and the same time from a plurality of coil-carrying reels, thereby reducing greatly the cost of production and also considerably 50 economizing in space, since a single standard serves to carry a plurality of reels, from which the coils can be reeled off, independent of and without interfering with one another.

The invention has for its further object to provide in connection with a reel-carrying and coil-receiving standard, a reel-receiving and supporting element in the form 55 of a horizontally disposed arm for support-

ing a reel for unreeling purposes, said arm comprising a pair of articulating or jointed members adapted to be locked in horizontal relation to each other, but also adapted to be brought into angular relation to each other for the purpose of more conveniently placing the reel in its operative position upon the reel-receiving arm, or for the purpose of removing the reel therefrom.

Other objects of the present invention not 65 at this time more particularly enumerated will be clearly understood from the following detailed description of the present invention.

With the various objects of the present invention in view, the said invention consists, primarily, in the novel standard for the purpose of mounting thereon a plurality of coil-carrying reels; and, the invention consists, furthermore, in the novel arrangements 75 and combinations of the several devices and parts, as well as in the details of the construction of the said parts, all of which will be more fully described in the following specification, and then finally embodied in 80 the clauses of the claims, which are appended to and which form an essential part of the said specification.

The invention is illustrated in the accompanying drawings, in which:—

Figure 1 is an elevation of a reel-receiving and carrying standard, showing in connection therewith one arrangement of a plurality of reels, said view representing one embodiment of the principles of the present 90 invention; and Figure 2 is a similar view of a reel-receiving and carrying standard, provided with reel-supporting arms of a modified construction, but still embodying the principles of the present invention.

Figures 3 and 4 are a side elevation and a plan or top view, respectively, on an enlarged scale, of one of the reel-supporting arms shown in the construction represented in said Figure 2, the hinged or articulated 100 members of the said arm being illustrated in straightened out relation; and Figure 5 is a side elevation of the said arm, showing the hinged members thereof in their angular relation and in position to receive a reel.

Similar characters of reference are employed in the said above described views, to indicate corresponding parts.

Referring now to the several figures of the drawings, it will be seen that the device 110

comprises a suitably formed base 1, which may be secured against tilting by means of a bolt 2, or other suitable fastening means, to the floor, or the like. Extending vertically from said base 1, by being suitably disposed in a tubular receiving portion of a hub 3 with which said base is provided, or by being otherwise secured to said base, is a standard or post 4. Suitably secured 5 upon said standard or post 4 are a plurality of supporting collars or sleeves 5, said collars or sleeves being preferably movably or slidably disposed upon said standard or post 4, so as to be adjustable with relation to 10 each other and the said standard or post, and each collar or sleeve being adapted to be secured, when so adjusted, in its fixed position upon the said standard or post 4, by means of a set-screw 6, or other suitable 15 fastening means. The reference-characters 7, 7, 7, see Figure 1 of the drawings, represent the previously mentioned reel-receiving and carrying arms or elements, each arm being provided with a perforated or tubular 20 hub 8, said hubs being adapted to be slipped over the said standard or post 4, and each hub being rotatably supported upon a sleeve or collar 5, substantially in the manner illustrated in said Figure 1. Similarly, the outer 25 free end-portion of each reel-receiving and carrying arm 7 is also provided with a perforated or tubular hub, as 9.

Rotatably disposed in the perforated or tubular hub 9 of each arm 7 is the lower 30 end-portion 11 of a reel-spindle 10, each spindle having suitably secured upon its lower end-portion 11 a supporting collar or flange, as 12, which rests directly upon the upper surface of the hub 9, so as to 35 maintain the operative relation of the spindle 10, and the parts carried by the spindle, as will be evident. Upon the upper end-portion of each spindle 10 is suitably mounted a socketed carrier-plate or element, 40 as 13, with which is suitably connected the coil-receiving reel 14 of any one of the usual and well-known constructions.

The operations of the several devices comprising the reel-carrier will be clearly understood from the foregoing description and 45 from an inspection of said Figure 1 of the drawings, and any further description of the same is therefore deemed unnecessary.

It will be readily evident from said drawing, that when the strands of wire leading from the respective coils mounted upon the several reels are fed into the variously located machines, that the various arms and the reels supported thereon will readily accommodate themselves to the pulling actions 55 from the leading-out wires, and that any one or more reels can be operated at one and the same time, and the unwinding action of each reel not interfering with the 60 unwinding action of the other reels.

While in the accompanying drawings, I have shown the standard or post 4 provided with a set of three arms 7, and a reel upon each arm, it will be clearly understood that the number of such arms 7 and reels 70 may be varied, according to the necessary requirements, without departing from the scope of the present invention.

In lieu of the single-form arms 7 shown and described in connection with said 75 Figure 1, reel-receiving elements or arms, comprising hinged or articulating members such as are shown in Figures 2, 3, 4 and 5 may be used.

In this construction each reel-receiving 80 element consists of a pair of members, as 15 and 16, the respective members being provided with pintle receiving ears or lugs, as 17 and 18, for pivotally connecting the said members by means of a pivot-bolt or 85 pin 19. At its free end, the member 15 is provided with a hole or perforation 20 for mounting it upon the standard or post 4 in the same manner as herein-above described in connection with the construction 90 shown in Figure 1 of the drawings. The other member 16 is provided at its free end with a receiving socket 21, or the like, in which is adapted to be arranged in the manner heretofore described, the lower end-portion 11 of a reel-spindle 10, as will be 95 understood from an inspection of Figure 2 of the drawings.

In order to maintain the straightened-out and fixed horizontal relation of the two members 15 and 16, the 100 member 15 is made with a socket 22, in which is movably disposed a bolt 23 adapted to be actuated by a spring 24, for forcing the end-portion of the bolt 23 into a correspondingly located socket 25 with which the 105 pintle-ear or lug 18 of the member 16 is provided, and as clearly indicated in dotted outline in Figure 3 of the drawings. To withdraw the end of the bolt 23 for its holding or retaining engagement with said 110 member 16 and to permit the said member 16 to drop from the position indicated in Figures 3 and 4 to the angular position shown in Figures 2 and 5, the bolt 23 is provided with a laterally extending lug, projection, or pin, as 26, projecting into and 115 movably disposed in an elongated opening or slot 27 in the side of the member 15, so that the said lug or pin 26 can be used as a manipulating means or finger-piece for 120 moving the bolt 23 in the direction of the arrow X, see Figure 3, to withdraw the bolt-end from the socket 25 of the member 16, as will be clearly understood.

To hold the said member 16 in its dropped 125 position, indicated in said Figures 2 and 5, against swinging movement when a reel and its coil of wire is to be placed in position, the said member has a projecting portion, as 28, which moves against the lower 130

surface 29 of the member 15, and thereby acts as a stop, as will be evident, bringing the said member into an immovable position to more easily place the end-portion 5 of the reel-spindle 10 in its position in the spindle-receiving socket of said member 16.

The purpose of this articulated or hinged arrangement of the members comprising the reel-receiving and carrying elements of the 10 device represented in said Figure 2, is to enable the use of reel-receivers and carriers with a main post or standard of considerable length, or of easily placing in position reels on which are placed very heavy coils of wire, 15 the reel and its coil being more readily placed in position, when the arm-member 16 has been dropped or lowered into the position shown at the top of said Figure 2, and the supported reel and coil, with 20 said member 16, then being easily swung into operative position, and locked or held in said operative position by the spring-actuated bolt 23 entering the receiving socket 25 of the said member 16.

25 Of course I am fully aware that changes may be made in the general arrangements and combinations of the several devices and parts, as well as in the details of the construction of the said parts, without departing from the scope of the present invention as set forth in the foregoing specification and as defined in the clauses of the claims which are appended thereto. Hence, I do not limit my invention to the exact arrangements and combinations of the various devices and parts as described in the said 30 specification, nor do I confine myself to the exact details of the construction of the said parts, as illustrated in the accompanying 35 drawings.

I claim:—

1. A reel-carrier comprising a standard or post, a plurality of reel-receiving ele-

ments, each element consisting of a pair of hinged members, one of said members being 45 connected with said standard or post, so as to extend laterally at a right angle therefrom, and means connected with the other member for rotatably mounting a reel thereon, a retaining means at the hinged portion of said members for holding said members horizontally in rigid relation, but adapted to be operated so as to allow the reel-carrier to drop and hang vertically with 50 relation to the member which is affixed to the standard or post, and means connected with said first-mentioned member slidably disposed upon said standard or post for 55 vertical adjustment of the entire reel-carrier upon said standard or post. 60

2. A reel-carrier comprising a standard or post, a plurality of reel-receiving elements, each element consisting of a pair of hinged members, one of said members being connected with said standard or post, so as to 65 extend laterally at a right angle therefrom, and means connected with the other member for rotatably mounting a reel thereon, a retaining means at the hinged portion of said members for holding said members horizontally in rigid relation, but adapted to be operated so as to allow the reel-carrier to drop and hang vertically with relation to the member which is affixed to the standard or post, and a tubular hub connected with 70 said first-mentioned member slidably disposed upon said standard or post for vertical adjustment of the entire reel-carrier upon 75 said standard or post.

In testimony, that I claim the invention 80 set forth above I have hereunto set my hand this 13th day of April, 1920.

GEORGE WOODWARD.
